UNITED STATES PATENT OFFICE

FELIX B. VOLLMAN, OF NEW YORK, N. Y.

DESIGN FOR A STICK PIN

Application filed July 24, 1929. Serial No. 32,188. Term of patent 14 years.

To all whom it may concern:

Be it known that I, FELIX B. VOLLMAN, a citizen of the United States, residing in the county, city, and State of New York, have invented a new, original, and ornamental Design for a Stick Pin, of which the following is a specification, reference being had to the accompanying drawing, forming a part thereof, wherein—

Figure 1 is a front elevational view of a stick pin embodying my design and in which

precious stones are cut to simulate the different parts of a flying machine.

Figure 2 is a side elevational view thereof;

Figure 3 is a plan view thereof looking down from above, and Figure 4 is a magnified view of Figure 1.

I claim—

The ornamental design for a stick pin, as shown and described.

FELIX B. VOLLMAN.
